Primary Examiner — Cynthia R Underwood

CLAIM

(57) The ornamental design for a hanger, as shown and described.

DESCRIPTION

FIG. 1 is a perspective view showing the hanger embodying the new design;

FIG. 2 is a front elevation view thereof;

FIG. 3 is a rear elevation view thereof;

FIG. 4 is a left side elevation thereof, the right side view is a mirror image thereof;

FIG. 5 is a top plan view thereof; and,

FIG. 6 is a bottom plan view thereof.

The broken lines in the drawing views are included for the purpose of illustrating unclaimed environment only, and forms no part of the claimed design.
